THERMOSTATIC EXPANSION VALVE

Earnest J. Dillman, Detroit, Mich., assignor to
 Detroit Lubricator Company, Detroit, Mich., a
 corporation of Michigan

Application February 18, 1946, Serial No. 648,462

8 Claims. (Cl. 236—92)

1

This invention relates to new and useful improvements in thermostatic expansion valves for refrigerating apparatus and more particularly to the type of valve in which the valve member operating means is responsive to the temperature and pressure of the refrigerant medium adjacent the outlet from the evaporator.

It is one object of this invention to provide a valve construction in which the necessity for sealing means between the valve controlled liquid line 10 passageway and the suction line passageway from the evaporator is eliminated thereby avoiding frictional and other opposing resistances to free operation of the valve member by its operating means.

The invention consists in the improved construction and combination of parts to be more fully described hereinafter and the novelty of which will be particularly pointed out and distinctly claimed.

In the accompanying drawings to be taken as a part of this specification, there are fully and clearly illustrated several preferred embodiments of the invention, in which drawings:

Figure 1 is a diagrammatic view of a refrigerating system showing the invention incorporated in a suction line type expansion valve which is in longitudinal central section,

Fig. 2 is a view partly in elevation and partly in longitudinal central section of a suction line valve showing another means for eliminating the operating rod packing,

Fig. 3 is a detail view in section on the line 3—3 of Fig. 2, and

Fig. 4 is a view similar to Fig. 2, but showing still another valve construction.

Referring to the drawings by characters of reference, I designates a refrigerant compressor which may be driven and controlled by any suitable means and which discharges compressed refrigerant medium into a condenser 2 and receiver 3 from which liquid refrigerant medium is fed through the liquid line 4 to the inlet 5 of the suction line expansion valve 6. Leading from the expansion valve outlet passageway 7 there is a conduit 8 connected to the evaporator 9 from which the refrigerant medium suction line or conduit 10 connects to the inlet fitting 11 of the expansion valve suction line passageway or pressure chamber 12 which has its outlet or pressure conduit fitting 13 connected by the suction conduit 14 to the inlet of the compressor 1.

The expansion valve casing has a cup-like member 15 which is closed by a resilient metal diaphragm 16 which forms the movable wall of the thermostatic power element 17 having a cover 18 which is hermetically sealed to the diaphragm 16 and member 15, as at 19. The power element chamber 20 is charged through a thereafter sealed filling tube 21 with a temperature respon-

sive volatile liquid such as Freon, for example. The casing member 15 has diametrically opposite apertures through its pressure chamber side walls to receive the conduit fittings 11 and 13, and has through its bottom wall an opening 22 concentric with the diaphragm 16. Sealed in the opening 22 there is a tubular valve body member 23 which extends into the passageway or chamber 12 and terminates adjacent the diaphragm 16. Adjustably screw-threaded on the body portion 24 within the passageway 12 there is a spring abutment member 25 which supports a helical coil spring 26 opposing expansion of the power element chamber 20 and movement of the diaphragm 16 upon temperature increase. The upper end of the spring 26 abuts a reinforcing plate 27 which fits against the diaphragm 16. The body member 23 projects externally of the casing member 15 and has a longitudinal passageway 28 therethrough which intersects the suction line passageway 12 and leads from the valve inlet 5 within the external body member portion 29. The passageway 28 has a valve seat member 30 with a valve port 31 therethrough concentric with the diaphragm 16. On the inlet side of the port 31 and engageable with the seat member 30 to close the port there is a valve member 32 which is carried by a valve operating rod 33 which extends longitudinally within the passageway 28 and into the suction line passageway 12 where it is secured to the reinforcing plate 27. On the outlet side of the seat member 30 there is a partition 34 having a guideway therethrough in which the rod 33 has a free sliding fit. Also, within and adjacent the suction line end of the passageway 28 there is a partition member 35 having a guideway through which the rod 33 also has a free sliding fit. In the side wall of the external body member portion 29 there is a cylindrical outlet recess 36 between the valve port 31 and the casing member 15. Through the bottom wall of the recess 36 there is an eduction passageway or outlet duct 37 which leads from the passageway 28 between the partition 34 and the guide or partition member 35. Concentric with the recess 36 and also opening through its bottom wall there is a discharge passageway or outlet port 38 which connects into the passageway 28 between the valve seat member 30 and the partition 34, that is, it leads from the valve outlet chamber 39. The eduction passageway 37 and the discharge passageway 38 have their longitudinal axes inclined or converging such as to meet within the outlet conduit 7 which is hermetically sealed in the recess 36. Within the outlet conduit 7 there is a hollow plug member 40 having a converging diverging bore 41 of Venturi form therethrough providing a throat. The plug member 40 terminates short of or is spaced from the bottom or end wall of the recess 36 so as to pro-

vide an annular chamber 42 into which the eduction passageway 37 discharges. The annular chamber 42 is formed by a nozzle portion or extension 43 of the discharge passageway 38 which extends concentrically into the converging portion of the bore 41 and terminates in spaced relation to the bore wall.

The operation of the valve of Fig. 1 is as follows: When the valve member 32 is open for the feeding of refrigerant medium to the evaporator 9, the refrigerant medium which discharges from the discharge passageway 38 into the plug member bore 41 will create a reduction of pressure on the eduction passageway 37 so that the pressure in the passageway 28 on the suction line side of the partition 34 will be reduced below the pressure in the valve outlet chamber 39. Accordingly any refrigerant medium which passes through the guideway in the partition member 34 will be drawn through the eduction passageway 37 into the outlet conduit 7 and be fed to the evaporator. The injector action of the cooperating discharge passageway 38 and Venturi bore 41 will reduce the refrigerant medium pressure in the passageway 28 between the partition 34 and the guide member 35 to such an extent that it will be less than the pressure in the suction line passageway 12 with the result that some superheated refrigerant medium may be drawn from the suction line passageway into the passageway 28 through the guide rod clearance in the guide member 35. The valve rod or stem 33 is therefore freely movable to transmit without frictional opposition any movement of the diaphragm 16 to the valve member 32, all without change in the desired response of the power element 17 to suction line temperature such as would be caused by leakage of refrigerant medium from the passageway 28 into the suction line passageway 12. Regulation of the valve member 32 in accordance with changes of temperature and pressure of the refrigerant medium in the passageway 12 which cause movement of the diaphragm 16 is well understood by those skilled in the art of thermostatic expansion valves.

Referring to Figures 2 and 3, the valve is of the same general construction as that in Fig. 1, but differs therefrom in the following respects: The valve is of the multiple outlet type and each outlet conduit 50 is itself formed with a Venturi like converging diverging portion 51 adjacent its body member outlet recess 52. Each conduit portion 51 thus provides a throat which is aligned coaxially with its valve chamber discharge outlet 53 which has an extension or nozzle.

Eduction passageways 54, 55 lead from the guide passageway 28 into the outlet conduits 50. Each eduction passageway 54, 55 has its longitudinal axis converging toward and intersecting the longitudinal axis of its respective discharge passageway, the point of intersection being in the outlet passageway adjacent the inlet to its respective converging bore portion. Refrigerant medium discharging through passageways 53, thus creates, in cooperation with the Venturi portions, a reduction of pressure in the eduction passageways and the passageway 28 between the partition 34 and the valve rod guide member 35. The operation of this construction will be apparent from the foregoing description of the operation of the valve of Fig. 1.

In Figure 4, the reduction of pressure in the passageway 28 between the partition 34 and the valve rod guide member 35 is obtained solely by

the aspirating effect of the refrigerant liquid discharging through the discharge passageways 60, 61 across the outlets of their respective eduction passageways 62, 63. In this construction of Fig. 4 both pairs of eduction and discharge passageways are inclined to the longitudinal axis of the passageway 28 and have their longitudinal axes converging at a point in the longitudinal center line of the respective outlet conduits 64, 65. The rest of the construction of this valve is the same as that of Fig. 1, the converging diverging portion of each of the outlet passageways being eliminated.

Having thus described my invention, what is claimed and is desired to be secured by Letters Patent of the United States is:

1. A thermostatic expansion valve, comprising a casing having a suction line passageway therethrough and having a second passageway intersecting said suction line passageway, said second passageway having an inlet and a valve port and having a partition therein with a guideway therethrough on the outlet side of said valve port, said casing having an outlet passageway with passageways leading thereto from said second passageway on the opposite sides of said partition, a valve member cooperable with said valve port, valve operating means responsive to changes of temperature and pressure in said suction line passageway, and a valve operating rod reciprocally fitting said guideway and said second passageway between said partition and said suction line passageway and operatively connecting said operating means and said valve member.

2. A thermostatic expansion valve, comprising a casing having a suction line passageway therethrough and having a second passageway intersecting said suction line passageway, said second passageway having an inlet and a valve port and having a partition therein with a guideway therethrough on the outlet side of said valve port, said casing having an outlet passageway with discharge and eduction passageways leading thereto from said second passageway, said discharge passageway leading from the valve port side of said partition, said eduction passageway leading from said second passageway between said partition and said suction line passageway, said discharge and eduction passageways having their longitudinal axes intersecting in said outlet passageway, a valve member cooperable with said valve port, valve operating means responsive to changes of temperature and pressure in said suction line passageway, and a valve operating rod reciprocally fitting said guideway and said second passageway between said partition and said suction line passageway and operatively connecting said operating means and said valve member.

3. A thermostatic expansion valve, comprising a casing having a suction line passageway therethrough and having a second passageway intersecting said suction line passageway, said second passageway having an inlet and a valve port and having a partition therein with a guideway therethrough on the outlet side of said valve port, said casing having an outlet passageway with discharge and eduction passageways leading thereto from said second passageway, said discharge passageway leading from the valve port side of said partition, said eduction passageway leading from said second passageway between said partition and said suction line passageway, said outlet passageway having a throat aligned with said dis-

charge passageway, a valve member cooperable with said valve port, valve operating means responsive to changes of temperature and pressure in said suction line passageway, and a valve operating rod reciprocally fitting said guideway and said second passageway between said partition and said suction line passageway and operatively connecting said operating means and said valve member.

4. A thermostatic expansion valve, comprising a casing having a suction line passageway therethrough and having a second passageway intersecting said suction line passageway, said second passageway having an inlet and a valve port and having a partition therein with a guideway therethrough on the outlet side of said valve port, said casing having an outlet passageway with discharge and eduction passageways leading thereto from said second passageway, said discharge passageway leading from the valve port side of said partition, said eduction passageway leading from said second passageway between said partition and said suction line passageway, said discharge passageway extending into said outlet passageway beyond the extent of said eduction passageway, a valve member cooperable with said valve port, valve operating means responsive to changes of temperature and pressure in said suction line passageway, and a valve operating rod reciprocally fitting said guideway and said second passageway between said partition and said suction line passageway and operatively connecting said operating means and said valve member.

5. A thermostatic expansion valve, comprising a casing having a suction line passageway therethrough and having a second passageway intersecting said suction line passageway, said second passageway having an inlet and a valve port and having a partition therein with a guideway therethrough on the outlet side of said valve port, said casing having an outlet passageway with discharge and eduction passageways leading thereto from said second passageway, said discharge passageway leading from the valve port side of said partition, said eduction passageway leading from said second passageway between said partition and said suction line passageway, said outlet passageway having a converging-diverging portion aligned with said discharge passageway, said discharge passageway terminating concentrically within the converging portion, a valve member cooperable with said valve port, valve operating means responsive to changes of temperature and pressure in said suction line passageway, and a valve operating rod reciprocally fitting said guideway and said second passageway between said partition and said suction line passageway and operatively connecting said operating means and said valve member.

6. A thermostatic expansion valve, comprising a casing having a cup-like member forming a suction line chamber with inlet and outlet connections, a temperature responsive power element having a pressure responsive diaphragm closing said cup-like member, a valve body member extending through the bottom wall of cup-like member concentric with said diaphragm and having a passageway therethrough, a valve seat member in said passageway, a partition in said passageway and having a guideway therethrough concentric with said seat member, said partition being positioned external of said cup-like member and forming a wall of the valve outlet chamber, a valve member cooperable with said seat member, an operating rod connecting said dia-

phragm to said valve member and having a free sliding fit in said guideway, a guide member in the suction line chamber end of said passageway and slidably receiving said rod, said body member having a side wall recess aligned with said partition and having a passageway connecting said recess to said body member passageway between said partition and said guide member, an outlet conduit sealed in said recess, a hollow plug fitting within said outlet conduit and extending into said recess, said plug having a Venturi type bore, and a nozzle extension on said body member projecting into said bore and having a discharge passageway therethrough leading from said valve outlet chamber.

7. An expansion valve, comprising a casing having a pressure chamber with a pressure conduit and a passageway leading therefrom, a temperature responsive power element having a pressure movable wall forming a side of said pressure chamber, said passageway having an inlet and an outlet port and an outlet duct and having a valve port between said inlet and said outlet port, said passageway having spaced partition members with aligned guideways therethrough and positioned at one side of said outlet port and on opposite sides of said outlet duct, a valve member cooperable with said valve port, an operating rod reciprocally fitting said guideways and operatively connected to said movable wall and to said valve member, said casing having an outlet passageway into which said outlet port and said outlet duct discharge in intersecting streams in close proximity so that the discharge from said outlet port will create a reduction of pressure in said outlet duct.

8. An expansion valve, comprising a casing having a pressure chamber with a pressure conduit and a passageway leading therefrom, a temperature responsive power element having a pressure movable wall forming a side of said pressure chamber, said passageway having an inlet and an outlet port and an outlet duct and having a valve port between said inlet and said outlet port, said passageway having spaced partition members with aligned guideways therethrough and positioned at one side of said outlet port and on opposite sides of said outlet duct, a valve member cooperable with said valve port, an operating rod reciprocally fitting said guideways and operatively connected to said movable wall and to said valve member, said casing having an outlet passageway into which said outlet port and said outlet duct discharge, said outlet passageway having a converging-diverging portion aligned with said outlet port, said outlet port having a nozzle extending into the outlet passageway converging portion, and said outlet duct discharging into said outlet passageway converging portion at the side of said nozzle.
